FLAT SPRAYING APPLIANCE

Filed Nov. 10, 1924

Fig. 1.

UNITED STATES PATENT OFFICE

HARRY D. BINKS, OF OAK PARK, ILLINOIS, ASSIGNOR, BY MESNE ASSIGNMENTS, TO BINKS MANUFACTURING COMPANY, OF CHICAGO, ILLINOIS, A CORPORATION OF DELAWARE

FLAT SPRAYING APPLIANCE

Application filed November 10, 1924. Serial No. 748,876.

My invention relates to spraying appliances of the class adapted to distribute a liquid in the form of a flattened spray for affording an even distribution of paints and 5 the like over the surfaces which are to be coated with such materials.

In such appliances, it has heretofore been difficult to secure both the desired fine atomization of the liquid together and a uniform 10 distribution of the latter in a substantially flat spray, such uniformity being highly important since a lack of it wastes material and also causes unsightly irregularities in the resulting coated surface. Furthermore, the 15 appliances heretofore devised for this purpose have been objectionable owing to the ready and frequent clogging of the ports by the drying of the liquid material in the same, and owing also to the large amount of time 20 which has to be spent in cleaning parts of the spraying appliance to get rid of the dried or partially dried paints or other liquids.

My present invention aims to provide a liquid spraying appliance, or more particularly 25 a head construction for such an appliance, which will effectively overcome both of the above named objections. With this in mind, my invention provides a spraying appliance having a head of exceedingly simple 30 construction and provides this head with air ports disposed for effecting an unusually fine and evenly distributed atomization of the liquid while also securing an unusual flattening of the resulting spray. Furthermore, 35 my invention provides constructions for this purpose which will be operative without requiring ports of such extremely small size as to clog readily, it being well known that the small bores heretofore employed in nozzle heads for such ports not only clog very 40 easily, but are difficult to drill with the desired exactness of direction, and also are difficult to clean.

More particularly, my invention provides 45 a nozzle head construction for this purpose in which the flattening effect is secured by directing one or more pairs of air jets obliquely forward against the projected stream of liquid in planes at right angles to the plane 50 along which the spray is to be flattened. It

also provides a spray head for this purpose in which the ports can readily be constructed by milling notches in the edge of one of the parts, thereby making these ports very easy to clean and in which such notches (or corresponding bores) can readily be provided in projections which also serve as handles whereby the corresponding part of the appliance can be rotated to shift the plane along which the spray is flattened. Moreover, my invention provides a spray head construction of this class which will be exceedingly simple and inexpensive, and one in which the part provided with the air ports can readily be interchanged without the use 55 of tools. Still further and also more detailed objects will appear from the following specification and from the accompanying drawings, in which

Fig. 1 is a central and longitudinal section 70 through the forward portion of a spraying appliance embodying my invention, namely one of the general type known in the trade as spray guns.

Fig. 2 is a perspective view of the rotatable 75 air port member.

Fig. 3 is a transverse section, taken along the line 3—3 of Fig. 1 to show the disposition of the air passages in the collar of the spray head with respect to the ports in the rotatable 80 member shown in Fig. 2.

Fig. 4 is a front view of the head of another spraying appliance embodying my invention, namely one provided with two pairs of parallel air ports formed by slots cut in 85 projections on the rotatable member.

Fig. 5 is a similar view showing another embodiment, namely one in which two pairs of parallel bores are employed in place of the slots shown in the embodiment of Fig. 4.

Fig. 6 shows the direction of the air jets by the embodiment of Fig. 4 with respect to the liquid stream and with respect to the plane along which the spray is to be flattened.

Fig. 7 is an enlarged elevation of the liquid stream projected by an appliance of my invention, with dotted lines indicating the tube of air which initially sheathes this liquid stream and also indicating the shape and relative disposition of the air jets impinging on 95 100

this stream from an embodiment employing an air-port member with two pairs of lateral ports.

Fig. 8 is a similar view showing a desirable size of the air jet directed against the liquid stream from an embodiment having only one pair of lateral ports, such as the embodiment of Fig. 2.

Fig. 9 is a perspective view of a rotatable air port member similar to that of Fig. 2, but with the slots entirely in the main portion and with digitally manipulated lugs spaced from these slots.

Illustrative of my invention as embodied in a so-called spray gun, Fig. 1 shows the forward portion of such an appliance, in which the body member 1 has a longitudinal bore 2 leading to an extension bore 3 in a nozzle core 7 which has an outlet 4 of relatively small diameter. This outlet is controlled by a needle valve 5, thereby regulating the flow of the paint or other liquid supplied under pressure to the bore 2 from a liquid inlet 26.

The forward end of the nozzle core 7 projects into the central bore of an air-port member 10 which is held in position by a retaining collar 6 threaded on the forward end of the body 1, the said central bore of the member 10 being sufficiently larger than the forward end of the nozzle core 7 so as to afford an annular outlet 8 (concentric with the liquid outlet 4) for the projection of air supplied through a bore 9 to the annular space between the exterior of the nozzle core 7 and the (desirably tapering) central bore of the air-port member 10. This member desirably has an exterior taper corresponding to that of an inwardly turned flange 11 on the collar 6 and is continuously forced into tight fitting relation to that collar by spring-pressed plungers 12, thereby leaving a space 13 behind the air-port member 10 for the distribution of compressed air from the air passage 9 to the aforesaid space and to channels in the interior of the collar 6.

To effect a flattening and spraying of the liquid stream projected through the liquid outlet 4, I provide the member 10 with one or more pairs of diametrically opposite air ports which may either be sawed, milled or drilled in the said member. These ports are all disposed for projecting jets of air at an incline against the stream of liquid projected through the liquid outlet 4 and along planes at right angles to the plane in which the resulting spray is to be flattened. Then I provide the collar 6 upon its interior with channels which permit air to pass from the space 13 behind the member 10 to the outer or inlet ends of the said ports. These passages are desirably provided in the form of two pairs (numbered in Fig. 3 as 14 and 26) respectively disposed along diameters at right angles to each other, so that the plane of the flattening can readily be shifted from

a horizontal to a vertical plane or vice versa by merely rotating the member 10 a quarter turn.

While the lateral air ports in the member 10 may be constructed in a variety of ways, I preferably form these by slotting the member 10 at its forward edge, and I desirably locate these slots in forwardly directed projections 15 formed on this member so as to afford ports of a considerable length, thereby insuring an accurate directing of the issuing air jets. Thus, Fig. 2 shows a simple form of this air-port member 10 in which the lateral air ports comprise a single pair of slots 16 diametrically opposite each other and each formed in a forward projection 15 on the said member. Each of the slots as thus provided desirably has an inclined inner wall, and these inner walls are disposed at equal angles with respect to the axis of the member so as to be in planes which will intersect each other on a straight line passing through the axis of the said member, namely the line 17 of Fig. 6, or a line disposed in the plane along with the spray is to be flattened. At the same time, the lateral walls of the slots 16 are disposed in planes parallel to the axis 18 of the said member and equi-distant from that axis, so as to serve as relatively long guides for accurately directing the resulting air jets and for preventing these air jets from spreading to any considerable extent while traversing the relatively short distance between the said ports and the liquid stream projected through the liquid outlet 4 of my appliance.

To prevent this liquid stream from spreading before the said air jets reach it, I employ the above described construction including the annular air outlet 8, thereby projecting through this outlet a tubular jet of air which forms a sheath 25 housing the cylindrical stream 19 of liquid. This tubular air sheath is desirably projected at considerably higher velocity than the liquid stream, thereby effectively preventing any material change in the size of this stream until the stream is reached by converging air jets from the lateral air ports. Moreover, I desirably make the ports 16 of such a width that the air jets issuing through them will be substantially as wide as the diameter of the liquid stream 19 when it impinges on this stream, as shown for example by the rectangular section 20 of such an air jet in Fig. 8.

However, the lateral air ports as thus employed need not consist of a single pair, as I may employ two pairs of parallel ports for this purpose, such as those formed by the relatively narrow slots 20 and 21 in Fig. 4. Or, I may provide an equivalent for such parallel pairs of slots for employing parallel bores 23 as shown in Fig. 5. In either of these last two mentioned cases, the ports formed in each side of the air-port member are preferably so close to each other and of such width that

the resulting air jets will impinge closely alongside each other against the liquid stream 19 and will cover the entire width of the latter, as shown for example in Fig. 7. This same relation is also shown diagrammatically in Fig. 7 for the parallel slotted air ports of Fig. 4, it being evident from this diagram of Fig. 6 that the jets from the two ports 20 are directed obliquely against each other and against a common portion of the liquid stream and that the same relation holds true of the two air jets issuing through the ports 21. In the latter case, each of these pairs of ports has its axial plane parallel to a line 24 passing through the axis of the liquid stream, but the said planes are spaced slightly from the axis 18 of the stream and are at opposite sides of the latter, it being noted also that the line 24 is at right angles to a line 17 in the plane 20 along which the spray is to be flattened.

Since the oppositely disposed ports of each pair tend to flatten the stream from opposite sides of the plane in which the line 17 is disposed, I secure an effective flattening along that plane. At the same time, the impinging of the lateral and oblique jets against the tubular air sheath 25 causes a dissemination of this air sheath and tends to flatten it along opposite sides of the flattened liquid stream.

This apparently aids both in securing an exceedingly fine atomization of the liquid and also in producing an unusual flattening of the latter, so that I am able to secure a spray of such a flat and fan-shaped form as to be highly effective for securing a uniform distribution of the liquid over the surface which is to be coated.

However, while I have herewith illustrated and described my invention in embodiments including certain highly desirable features of construction and arrangement, I do not wish to be limited to these since many modifications might obviously be made without departing either from the spirit of my invention or from the appended claims. Nor do I wish to be limited to a particular construction of the air ports in the corresponding member, although I preferably employ slots for these purposes, since such slots can readily be sawed quite accurately and also make it very easy to remove any material gathering in them.

For example, the slots need not extend through the projections which serve as handles for rotating the air port member from one position to another, but might be spaced from these slots, as shown in Fig. 9. In that case, the air-port member 10A has the digitally manipulable lugs 31 spaced from the slots 32, these slots being entirely in the main body portion.

I claim as my invention:—

1. In a flat-spray producing appliance, means for projecting a forwardly directed stream of liquid, and an air-port member

mounted for rotational adjustment about the axis of the said stream and having at the radially outer edge of its forward end a pair of diametrically opposite notches having flat sides parallel to the axis of the stream, the said flat sides of each notch alining respectively with those of the opposite notch. 70

2. In a spraying appliance, means including a tubular outlet for projecting a concentrated stream of liquid, an annular air-port member concentric with the said outlet and having at the radially outer edges of its forward end a pair of diametrically opposite notches, means laterally confining the said member to afford outer walls for the notches, and means for projecting air through the notches. 75

3. In a flat-spray producing appliance, a body member provided with liquid supply and air supply passages, a sleeve mounted on one end of the body member; a ported member secured to the body member by the sleeve, the ported member having an axial opening and having a pair of projections disposed at opposite sides of the axis of the said member and projecting forwardly beyond the sleeve, each projection having a slot at its radially outer edge for communicating with the air supply passage, the said projections serving also as handles whereby the ported member can be rotated with respect to the body member. 85 90

4. In a flat spray appliance, a frontal nozzle member having a central air outlet and having two diametrically opposed forwardly directed projections, each projection having a supplemental air outlet open forwardly and presenting its radially inner end forwardly of the forward end of the said central outlet, the said supplemental air outlets comprising a flat sided slot formed in each projection with each side thereof parallel to the axis of the central air outlet and parallel to the other side. 100 105

5. A spray appliance as per claim 4, in which the said parallel slot sides are disposed at opposite sides of and equidistant from the said axis. 110

Signed at Chicago, Illinois, November 3, 1924.
